UNITED STATES PATENT OFFICE

CARL D. SALISBURY, OF CLEVELAND, OHIO, ASSIGNOR, BY MESNE ASSIGNMENTS, TO
THE WINTON ENGINE CORPORATION

AUXILIARY PUMP SYSTEM FOR V TYPE ENGINES

Application filed May 26, 1930. Serial No. 455,617.

This invention relates to internal combustion engines, and the invention has to do with the location and drive of the engine pump auxiliaries. The invention is particularly applicable to engines of V type for marine service.

It will be appreciated that in the usual marine installation the hull into which the engine is fitted allows but very little clearance space for auxiliaries about the engine. Where the engine is of V type and consequently of greater transverse dimensions than the more usual in-line type, it is not practical to locate auxiliaries at the side of the engine. The after end of the engine is usually also relatively inaccessible; but the forward end where it is customary to locate the controls is relatively accessible.

Where the engine is designed to operate on a fuel injection cycle, the number of pump auxiliaries is increased at least by the number of fuel pumps, and it is particularly important that all of the pumps, constituting as they do the hearts of their respective circulating systems, be most accessible. Development in the engine art has greatly improved the reliability of engine operation as a whole and of the principal primary working parts, but the pumps from their nature must still usually have frequent attention.

It is the object of this invention to arrange all of the pumps at one end as at the forward end of the engine, in such relation that each will be fully accessible, and to arrange a drive for all of the pumps which shall be of such reliability that it may be from the opposite or after end of the engine.

The exact nature of this invention together with further objects and advantages thereof will be apparent from the following description taken in connection with the accompanying drawings, in which Fig. 1 is generally an elevation of such an engine from the forward end and therefore showing particularly the pump auxiliaries thereof, parts being broken away to show details of construction; Fig. 2 is a conventionalized plan view of the engine; Fig. 3 is a detail showing the driving engagement of the auxiliary crank shaft.

With reference now to the drawings, the

principal primary parts of the engine are those of the usual V engine including a pair of rows of cylinders arranged in angular relation and having head portions 1; a crank case 2 with which the cylinders are secured; 55 it being understood that within the cylinders are pistons arranged to drive the engine shaft 3 through connecting rods acting on cranks on the crank shaft; the cylinders being provided with valves driven by valve gear actuated in timed relation with the engine crank shaft through gear located in the housing 4; all as will be well understood by one familiar with the art.

According to my invention I arrange 65 transversely across the forward end of the engine an auxiliary crank shaft 5 carrying a gear 6 by which the shaft may be driven. To this end an auxiliary shaft 7 is arranged between the cylinder blocks 1, driven at its 70 after end by suitable driving connection within the gear housing 4, and carrying at its forward end a pinion 8 meshing with the gear 6.

On either side of the auxiliary crank shaft 75 5, as thereabove and therebelow and thus disposed generally in a plane, are the auxiliary pumps for the engine. Each of these pumps is driven by one of the cranks of the shaft 5 and several of the pumps may preferably 80 be in tandem relation. Thus four single-acting oil pump cylinders 9 are shown, two for pressure and two for scavenging, each having a piston 10 and a connecting rod 11 bearing on the crank shaft 5 for the purpose. Below 85 and aligned with the oil pumps are water pumps 12, double-acting, and the piston 13 of each having connection with the piston 10 of its corresponding oil pump through a connecting rod 14; which arrangement will 90 be recognized as what is known as tandem.

Above the crank shaft 5 is a bank 15 of fuel pumps including a pump plunger 16 for each crank of the shaft. The upper end of each plunger 16 moves in an insert 17 providing a pump cylinder, and the lower end of each plunger is carried by a cross-head 18 connected with the crank shaft 5 by a connecting rod 19 and slidably in a guide 20.

In the construction shown the oil and wa- 100

ter pumps are provided with automatic valves while the fuel pumps are provided with valve gear including the parts 21 and taking motion from the pump plunger.

- 5 It will be apparent from the foregoing description that although the pump auxiliaries for the engine include twelve pump units, all are driven from a single crank shaft, and all are located most advantageous-
10 ly for access. Preferably a housing 22 is provided about the pumps, suitable cover plates being of course provided for the front end of the housing.

What I claim is:

- 15 1. In an internal combustion engine, an auxiliary crank shaft positioned transversely of said engine at an end thereof and arranged to be driven thereby, and pump auxiliaries to the engine, driven by said crank shaft and ar-
20 ranged thereabove and therebelow and including pairs of pistons arranged in tandem relation.
2. In an internal combustion engine of V type, and having a timed shaft arranged
25 along and between the rows of cylinders thereof, an auxiliary crank shaft arranged transversely of said engine at an end thereof and arranged to be driven by said timed shaft, and pump auxiliaries to the engine
30 driven by said transverse crank shaft and arranged thereabove and therebelow.
3. In an internal combustion engine of V type for marine service, an auxiliary shaft arranged along said engine between the rows
35 of cylinders thereof, an auxiliary crank shaft arranged transversely of said engine at the forward end thereof and arranged to be driven by said auxiliary shaft, pump auxiliaries to the engine driven by said
40 crank shaft and arranged thereabove and therebelow and including pairs of pistons arranged in tandem relation, and gear at the after end of said engine for driving said auxiliary shaft from the engine crank shaft.
- 45 In testimony whereof I hereby affix my signature.

CARL D. SALISBURY.
